UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

LOCKING AND ADJUSTING MECHANISM.

1,286,468.

Specification of Letters Patent.

Patented Dec. 3, 1918.

Application filed March 17, 1917. Serial No. 155,554.

To all whom it may concern:

Be it known that I, RICHARD LESTER WILCOX, a citizen of the United States, residing at Waterbury, in the county of New Haven and State of Connecticut, have invented certain new and useful Improvements in Locking and Adjusting Mechanism, of which the following is a specification, reference being had therein to the accompanying drawings.

My invention refers to a new and improved locking and adjusting mechanism, more particularly as it relates to means for locking and adjusting an independent member, as a block, within a movable gate.

It is the object of my invention, among other things, to provide a simple and effective device, for the general purpose above indicated, that will have a minimum number of parts requiring manipulation by the operator, and in which there will be practically no possibility of a strain upon any of the parts to throw them out of alignment.

To these, and other ends, my invention consists in the locking and adjusting mechanism, having certain details of construction and combinations of parts, as will be hereinafter described and more particularly pointed out in the claims.

Referring to the drawings, in which like numerals of reference designate like parts in the several figures;

Figure 1 is a side elevation of my improved mechanism, partly in section;

Fig. 2 is a fragmentary plan view of the gate and the parts adjacent thereto;

Fig. 3 is a plan view of the gate block; and

Fig. 4 is an end view thereof.

My improved mechanism is adapted to be used upon any type of machine having a member operated from a connection or pitman, one end of which may move in either a rotary or a straight path, and the other connected with the device herein shown, while the member itself reciprocates in guideways, the connection between the pitman and reciprocating member being adjustable.

Mechanism of this general character is common to heading machines, and I have therefore adopted so much of the elements of this type of machine as is necessary to

describe my invention, calling attention, however, to the fact that it is not limited solely to this class of machinery.

Heretofore it has been the practice to secure the block within the gate by two or more screws arranged so that they pass through the gate upon each side thereof and impinge against the block. In certain forms of such machinery this form is objectionable, because the operator, either through forgetfulness or carelessness, fails to uniformly adjust all of the screws, thereby permitting lost motion upon one side and an irregular instead of a uniform wear upon the parts.

Then, again, as the screws are adjacent to the sides of the gate, they are liable to spread and cramp the gate in its bearings so as to either prevent its movement entirely or create such additional friction as to make it practically inoperative, or throw it out of alignment, so that the punch and dies do not register with each other.

These, and other objections are eliminated in my invention, wherein only a single screw is used and is so placed as to prevent cramping or strain upon the gate parts.

The portion of the bed of the machine shown in the drawings is designated by the numeral 1, and in which the gate 2 is slidably mounted, receiving its movement from a pitman 3, which is connected with the gate by means hereinafter described, and the end of which, (not shown), moves in a rotary path, as is common in the art. On the front end of the gate is the punch block 4 having punches 5 mounted therein. The gate is constructed with rearwardly projecting side plates 6, each provided with slots 7, in which is movably mounted the gate block 8. The projecting rear ends of the plates 6 are secured together, against any tendency to spread, by the cap 9, secured in place by the screws 10, and having the lips 11 thereon, that engage lips upon the said plates, thereby insuring a very strong and rigid structure.

Mounted within the gate block is a shaft 12, to which the pitman 3 is secured by the cap 13 and bolts 14.

The means for adjusting the gate block 15 relatively to the gate, comprises a wedge that lies between said block and the face 16 in the gate, and which is adjustable in

one direction by a screw 17, which is threaded through a head 18 upon said wedge and impinges upon the top of said gate block, a jam nut 19 locking said set screw in any of its adjusted positions.

The locking mechanism comprises a single screw 20, threaded through the hood portion 21 of the gate that ties the plates 6-6 together upon their top sides, said screw abutting against a shoulder 22 in the top of said gate block and is locked in its adjusted positions by a jam nut 23. This screw 20 is located midway between the sides of the gate 2, and as the hood member 21 is a substantially heavy construction there is no possibility of the gate feeling any lateral strain from said screw and only a single screw is required instead of two, as heretofore.

To adjust and lock the gate block, the screw 17 is actuated so as to shift the position of the wedge 15, after which the screw 20 is manipulated to hold said block against the wedge, as is clearly illustrated in Fig. 1 of the drawings. Therefore, to adjust and lock said gate block only two screws are required and these operate upon different members.

There are minor changes and alterations that can be made within my invention, aside from those herein suggested, and I would therefore have it understood that I do not limit myself to the exact construction herein shown and described but claim all that falls fairly within the spirit and scope of the appended claims.

Having described my invention, what I claim as new and desire to secure by Letters Patent, is:

1. In a device of the character described, the combination with a member; of a second member movably mounted therein; and means for adjusting said second member within said first member and locking it in such adjusted position, comprising a movably mounted element having engagement with said second member, means for imparting movement thereto, and means within said first member and engaging said second member for holding this latter member in engagement with said element.

2. In a device of the character described, the combination with a member having openings therein; of a second member movably mounted within said openings; an adjustable member mounted in said first member and by its position limiting the movement of said second member in one direction; and a locking member movably mounted in said first member and engaging said second member at a point between said openings to prevent its movement away from said adjustable member.

3. In a device of the character described, the combination with a member having openings in the sides thereof; means con-

nected with said member for preventing the relative movement of said sides adjacent to said openings; a second member movable within said openings; an adjustable member mounted in said member and having a relative movement therein at an angle to said second member; and a locking member movably mounted in said first member and engaging said second member to prevent its movement away from said adjustable member.

4. In a device of the character described, the combination with a member having side portions with openings therein and a hood portion connecting the same; of a block movable within said member; an adjustable element movable within said member at an angle to said block; and a locking member movably mounted within said hood portion and holding said block against relative movement within said member.

5. In a device of the character described, the combination with a member having side portions with openings therein and a hood portion connecting the same, of separable means for securing said side portions against relative movement; a block movable within said member; an adjustable element movable within said member at an angle to said block; and a locking member movably mounted within said hood portion and holding said block against relative movement within said member.

6. In a device of the character described, the combination with a member having side portions with openings therein and a hood portion connecting the same; of a cap member having an intermeshing engagement with said side portions for securing the same against relative movement; a block movable within said member; an adjustable element movable within said member at an angle to said block; and a locking member movably mounted within said hood portions and holding said block against relative movement within said member.

7. In a device of the character described, the combination with a member having side portions with openings therein and a hood portion connecting the same; of a block movable within said member; an adjustable element movable within said member at an angle to said block; a threaded member within said adjustable element and engaging said block; and a locking member movably mounted within said hood portion and holding said block against relative movement within said member.

8. In a device of the character described, the combination with a member having side portions with openings therein and a hood portion connecting the same; of a block movable within said member; an adjustable element movable within said member at an angle to said block; and a locking

member movably mounted within said hood portion at an angle to said block and holding said block against relative movement within said member.

- 5 9. In a device of the class described, a movable member; a connecting block mounted therein; a shaft mounted in said block; motion transmitting means connected with said shaft; a wedge member interposed between one face of said movable member and said block; means for adjusting said wedge member and imparting substantially downward pressure to said block; and means supported by said movable member imparting 10 pressure on said block at an angle to said downward pressure substantially in an inclined plane.

10 10. In a device of the class described, a movable member having a power transmitting member connected thereto by means of a block adjustably held with relation to said movable member by means of a wedge member having a tendency to move said block in one direction and an adjustable 25 device imparting pressure at an angle to the pressure imparted by said wedge member.

11. In a device of the class described, a connecting block held within a body member by a wedge member movable relatively 30 to said block by means of a device mounted on said wedge member and bearing on said block; and an additional adjusting device having a support rigid with said body member and bearing on said block at a different 35 angle to that of the other adjusting device.

12. In a device of the class described; a movable member; a power transmitting member connected with said movable member; and means for connecting said members, said means comprising an adjustable wedge member, a wedge-like block rigidly held in said movable member, means for adjusting said wedge member, and a retain-

ing and locking device mounted upon said movable member and bearing on said block at a central point thereof.

13. In a device of the class described; a body member; a connecting block rigidly mounted and held within said body member; a plurality of adjusting and retaining screws bearing on said block; and a wedge member interposed between said block and said body member, one of said screws lying in a plane substantially at right angles to said block, being employed to adjust said wedge member, and the other screw lying in a plane substantially inclined relatively to said block, being employed to retain said block in place.

14. In a device of the class described; a body member; a power transmitting member; a connecting block held within said body member uniting the latter member with the power transmitting member; a wedge member interposed between said body member and said block; adjustable members bearing on said block at substantially different angles and held by rigid supports provided by said members; one of said adjustable members 70 acting to change the position of said wedge member and the other adjustable member serving to lock said block in position.

15. In a device of the character described; a body member; a power transmitting member; a connecting block having a centrally located angularly disposed recess therein and slidably mounted between projections of said body member; and an adjustable retaining means for said block carried by a member mounted on said body member engaging said angularly disposed recess in a manner so as to impart pressure upon said block substantially diagonal to the path of travel thereof.

In testimony whereof I have hereunto affixed my signature.

RICHARD LESTER WILCOX.
